UNITED STATES PATENT OFFICE.

CLAUD L. LONG, OF DAYTON, OHIO, ASSIGNOR TO THE CRAWFORD, McGREGOR AND CANBY COMPANY, OF DAYTON, OHIO, A CORPORATION OF OHIO.

MACHINE FOR HOLLOWING SHOE LASTS.

Application filed April 17, 1924. Serial No. 707,300.

This invention relates to shoe last manufacture, and more particularly to a machine for recessing or hollowing shoe lasts for shoe display purposes.

5 While lasts for shoe manufacturing purposes are ordinarily of solid construction, there is the demand for a shoe form for shoe display purposes, and as fillers for keeping shoes in proper shape and contour, for which 10 purposes, the ordinary shoe last is unnecessarily heavy. To meet this demand hollow shoe forms are provided by turning the ordinary shoe last and then recessing the bottom of the last quite deeply the recess follow- 15 ing in general the contour of the last, leaving a hollow thin walled form. The usual method of producing such hollow forms has been by hand operation, or by means of an auger bit, against which the last to be hollowed is held by hand, the last being tilted 20 and moved to and fro to present it in different relation with the bit. Such operation is not only dangerous, but the product is un-uniform, and the operation is uneconomical 25 from a manufacturing standpoint. The present invention contemplates the movement of a universally adjustable cutter head, in relation with a stationarily held last, and controlling and limiting its movement by a 30 master model of hollow form, within which operates a tracer. In the present construction, the revoluble dependent cutter is belt driven from an electric motor and carried upon an adjustable supporting arm having 35 a gimbal mounting upon a reciprocating table. The cutter and its supporting arm are capable of both vertical and lateral oscillation, with reference to the stationarily held work, about the pivots of the gimbal mount- 40 ing, while it is movable to and fro, in a fore and aft direction, by the sliding adjustment of the sliding table.

The object of the invention is to simplify 45 the structure as well as the means and mode of operation of such hollow last forming devices, whereby they will not only be cheapened in construction, but will be more efficient in use, positive in operation, uniform in action and unlikely to get out of repair.

50 A further object of the invention is to provide means for hollowing shoe lasts and the like, in which the operation may be controlled to produce duplication of a previously formed recess or cavity, which may 55 include under-cut portions.

A further object of the invention is to provide improved driving connections and an adjustable mounting for such cutter.

A further object of the invention is to provide an improved form of cutter head 60 for operating within a recess or cavity.

With the above primary and other incidental objects in view as will more fully appear in the specification, the invention consists of the features of construction, the 65 parts and combinations thereof, and the mode of operation or their equivalents as hereinafter described and set forth in the claims.

Referring to the accompanying drawings, 70 wherein is shown the preferred, but obviously not necessarily the only form of embodiment of the invention, Fig. 1 is a top plan view of the assembled machine. Fig. 2 is a side elevation showing the cutter and its 75 supporting arm in elevated and retracted position to enable the insertion and removal of the last. Fig. 3 is a rear end elevation illustrating the gimbal mounting of the cutter arm and the sliding table. Fig. 4 is a 80 front elevation of the assembled machine. Fig. 5 is a perspective view of a hollow shoe form produced by the present machine. Fig. 6 is a detail view of the cutter head. Fig. 7 is a transverse sectional view on line 7—7 85 of Fig. 6 and Fig. 8 is a transverse sectional view on line 8—8 of Fig. 6.

Like parts are indicated by similar characters of reference throughout the several views.

In the accompanying drawings, 1 indicates the base at the forward end of which is located a support 2 for the last 3 to be operated upon, and also for the model or guide 4. Any suitable means may be employed for securing the last to be operated upon and model or pattern form upon the support. In the present instance, clamp jaws have been shown for this purpose. The work support 2 is preferably though not necessarily mounted for oscillatory adjustment upon trunnions 5, pivoted in standards 6 and held in adjusted position by an adjustable link 7. Slidably mounted upon the base 1 for reciprocatory movement in a 100 fore and aft direction, that is to say, to and from the work support 2, is a sliding table or carriage 8. This reciprocatory carriage 8 is preferably mounted upon rollers or upon ball bearings 9, to facilitate to and fro move- 105 110

ment. The carriage 8 moves quite freely in either direction. Pivotedly mounted upon the reciprocating carriage 8 for rotation about a vertical axis is a yoke 10, in which 5 in turn is pivoted upon a horizontal axis the driving motor 11. Extending forwardly from the driving motor 11 and toward the work support 2 is a supporting arm 12, which for purposes of adjustment and to 10 afford convenient means for tightening the drive belt is preferably, though not necessarily formed in two interconnected and relatively adjustable sections. These sections of the arm 12 are held in their adjusted relation by the clamp nut 13. At its forward end, the arm 12 is provided with a bearing head 14, in which is revolvably mounted a spindle carrying at its upper end a small driven pulley interconnected by the belt 16 15 with the drive pulley 17, upon the upper end of the armature shaft of the motor 11. The spindle 15 carries at its lower end a bulbous cutter head 18, by which the excess material is removed from the last 3, and the 20 interior of the last hollowed to correspond with the pattern or model 4. Projecting laterally from the arm 12, but fixedly connected therewith for movement in unison is a supporting arm 19, having at its extremity 25 a head 20, from which projects in dependent relation a tracer stem 21, having a bulbous tracer head 22, corresponding in its shape and proportions with those of the cutter head. This tracer head 22 by its engagement within the recess 4' of the model or 30 pattern last 4, limits the range of cutting action of the cutter head 18 within the last 3 being operated upon. The head 20 of the tracer arm, carries a knob or handle 23, 35 while the arm 12 has projecting laterally therefrom a second handle 24. The operator standing in front of the work support 2, and grasping the handles 23 and 24 controls the operation of the machine by swinging it 40 from side to side, raising and lowering the tracer and cutter head, and pushing and pulling it to and fro within the limits defined by the recess 4' of the model or pattern. The gimbal mounting afforded by the yoke 45 10 enables substantially universal adjustment of the arm 12, and maintaining in all positions constant driving relation with the motor 11. At the same time the reciprocating movement of the carriage or table 8, 50 enables the operation of the device over a comparatively large area. A standard or rest 25 supports the arm 12 in elevated relation when not in use, and in a retracted position, which permits the insertion and removal of lasts and an interchange of patterns or models without interference.

While various forms of cutter heads 18 or other tools may be employed, the preferred form of such cutter is of ovoid form, 60 consisting of two substantially spoon shaped

cutter blades 26, detachably secured to a head 27 upon the lower end of the spindle 15. The convex outer faces of the spoon shaped blades 26 are slightly eccentric in relation with each other, to provide clearance. In 70 practice, a bulbous cutter head has been employed in which the cutting blades 26 are integral with each other, and also with the attaching motion of the head. However, for convenience of repairs and for sharpening the blades, it is desirable that they be made independent and be detachably secured to the support. 75

In operation the entire device is drawn forward until the cutter head 18 is positioned above the last 3. It is then pushed downward, cutting into the last until the tracer head 22 engages with the bottom of the recess or cavity 4' in the model last. The cutter head 18 is then moved to and fro 80 transversely by oscillating the arm 12 about the pivotal mounting of the yoke 10 and is moved fore and aft by the sliding movement of the table or carriage 8, until limited by the engagement of the tracer head 22 with the lateral walls of the recess or cavity 4', 85 in the model or pattern last. The bulbous form of the cutter head allows the recess or cavity to be undercut or inwardly widened through the heel portion and arch portion of the last. By following the interior walls of the recess 4' with the spacer head 22, the cutter head 18 is caused to follow the same course of travel within the body of the last 3, and by its removal of excess material 90 duplicates the recess of the model or pattern last. By this means the interior of the last can be contoured with extreme accuracy to afford comparatively thin walls of uniform thickness throughout, or with such 95 variations of contour and thickness as may be present in the model. 100

It has been found in practice that a skilled workman, by exercise of judgment and care can recess a last to the required extent without the use of the model and tracer. In such case the cutter is moved to and fro as before described, but without the limitations imposed by the model. Reliance is placed 110 entirely upon the skill and judgment of the workman together with a certain sense of "feel" which is the development of a skilled artisan. Models are initially produced by such method and by a skilled operator, to be subsequently employed by less skilled workmen for duplication by means of the tracer 115 method of movement limitation. 120

While the machine is described as producing but one duplication of the recessed model at a time, it is obvious that the head may be provided with multiple spindles and cutters operating simultaneously upon a number of different lasts and controlled from the same master model. Such arrangement is indicated by dotted lines in Fig. 1. 130

From the above description it will be apparent that there is thus provided a device of the character described possessing the particular features of advantage before 5 enumerated as desirable, but which obviously is susceptible of modification in its form, proportions, detail construction and arrangement of parts without departing from the principle involved or sacrificing 10 any of its advantages.

While in order to comply with the statute the invention has been described in language more or less specific as to structural features, it is to be understood that the invention is 15 not limited to the specific details shown, but that the means and construction herein disclosed comprises the preferred form of several modes of putting the invention into effect and the invention is, therefore, claimed 20 in any of its forms or modifications within the legitimate and valid scope of the appended claims.

Having thus described my invention, I claim:

25 1. In a machine of the character described, stationary work and model supports, an electric motor movable toward and from the work and model supports, a reciprocatory mounting for the motor upon which the motor is mounted for oscillatory movement about both vertical and horizontal axes, an 30 arm fixedly connected with the motor and movable in unison with the reciprocatory and oscillatory movement thereof, a tracer 35 gage for engagement with the model, a revoluble cutting tool for engagement with the work carried by the arm, and a drive belt therefor, operatively connecting the cutting tool with the electric motor said tracer being enabled to follow the model by the to 40 and fro reciprocatory movement of the motor mounting in conjunction with the vertical and lateral swinging movements of the arm to enable the cutter to follow the same 45 lines of movement upon the work.

2. In a machine of the character described, a work holder, a cutting tool revolving on

a vertical axis, an adjustable carrier for the tool, movable longitudinally, transversely and vertically relative to the work holder, a tracer in fixed relation with the tool and movable to and fro in unison therewith, an electric motor located in fixed relation with the cutter and movable in unison therewith, and an operative driving connection between the motor and the cutter by which the cutter is uniformly operated in all positions of adjustment.

3. In a machine of the character described, a stationary work holder, a sliding carriage mounted for reciprocatory movement toward and from said work holder, a motor mounting upon the carriage capable of oscillatory movement to and fro about an axis perpendicular to the plane of movement of the carriage, a motor pivoted in said mounting for oscillatory movement about an axis substantially perpendicular to the axis of oscillation of the motor mounting, an arm fixedly attached to the motor and radially disposed in relation with the axes of oscillation of the motor, a revoluble cutter rotating on a substantially vertical axis and a tracer located in fixed relation with the cutter carried by the arm and a drive belt affording operative connection between the motor and cutter for operating the cutter in all positions of adjustment of the arm and motor.

4. In a machine of the character described, stationary work and model holders, a revoluble cutter rotating about a substantially vertical axis, a driving motor operatively connected with the cutter, a tracer gage mounted in fixed relation with the cutter, and a mounting upon which the cutter and motor are mounted in relatively fixed relation with each other, but capable of to and fro horizontal, and vertical and transverse swinging movements, the relative relation of the driving motor and cutter being maintained constant in all positions of adjustment.

In testimony whereof, I have hereunto set my hand this 8 day of April, A. D. 1924.

CLAUD L. LONG.
